UNITED STATES PATENT OFFICE.

JAMES L. JACKSON, OF NEW YORK, N. Y.

DESIGN FOR HARNESS SADDLE-BRACKET.

Specification forming part of Design No. 5,397, dated December 5, 1871.

To all whom it may concern:

Be it known that I, JAMES L. JACKSON, of the city and State of New York, have invented or produced a new and original Design for Harness-Bracket; and the following is declared to be a correct description of the same.

This design relates to the general shape or configuration of the bracket.

In the drawing, the said bracket is represented by a perspective view.

The back plate *a* is to be of the ornamental shape shown, and provided with a center or name plate. The portion *c* of the bracket is made as an open-work shell, and projects from the back plate *a*, and it is hollowed to conform to the shape of the pads on the harness-saddle. The part 2 of

this bracket *c* is near flat, so that the slightly concave portion *c* may be at the necessary distance from the wall to allow the saddle of the harness to be hung thereon without coming into contact with the wall. The general configuration of the bracket-shell is clearly shown in the drawing.

I claim as my invention—

The design of the shape and configuration of the harness saddle-bracket, substantially as described and shown.

Signed by me this 13th day of July, A. D. 1871.
JAMES L. JACKSON.

Witnesses:

HAROLD SERRELL,
GEO. T. PINCKNEY.
